FLUID DRIVE

Richard M. Nelden, Birmingham, Mich., assignor to American Radiator & Standard Sanitary Corporation, New York, N.Y., a corporation of Delaware
Filed June 23, 1960, Ser. No. 38,160
8 Claims. (Cl. 60—54)

This invention relates to a fluid drive, and particularly to a variable speed fluid drive having improved means for partially or wholly declutching the runner during periods of impeller acceleration and output shaft overload.

In conventional fluid drive arrangements of the variable speed type there is employed a vaned impeller and a vaned runner cooperating together to define a work chamber. The impeller is carried by the input shaft which may be directly or indirectly driven by a prime mover such as an electric motor or gasoline engine. The runner is connected to the output shaft which drives the load. A fluid-confining casing extends around and beyond the impeller and runner to define a chamber for receiving the power fluid from the work chamber. This receiving chamber houses a fluid-withdrawing means which in the usual case consists of one or more scoop tubes which dip into the fluid within the chamber and convey the fluid out of the fluid coupling and thence into a sump. The sump supplies hot fluid to a pumping mechanism which circulates all or part of the fluid through a cooler structure before returning it into the work chamber defined by the aforementioned runner and impeller.

It will be understood that the drive from the vaned impeller to the vaned runner is derived from the rapidly whirling or vortically travelling fluid located within the work chamber. With relatively small quantities of fluid within the work chamber the motion of the impeller is only partially transmitted to the runner, i.e., there is a slippage, which may vary depending on the fractional extent to which the work chamber is filled. When the work chamber is completely filled the slip is at a minimum, and there is substantially a one-to-one drive from the impeller to the runner.

The fluid level in the work chamber is determined by the position of the previously mentioned scoop tubes which are located in the scoop chamber. In the usual case an external control is provided for determining the position of these scoop tubes, the arrangement being such that when the control is suitably operated to dispose the lips of the scoop tubes adjacent the outer periphery of the scoop chamber the fluid level is reduced so as to correspondingly reduce the operating level in the work chamber. When the control is actuated to dispose the scoop tube lips away from the outer periphery of the scoop chamber the level of the fluid ring is increased so as to accordingly increase the filling of the work chamber and thereby reduce the slip existing between the impeller and runner.

During certain operational periods of the fluid drive, as for example during periods of impeller acceleration and during other periods of output shaft overload, it is desirable to partially or wholly disconnect the impeller from the runner. The impeller-runner connection is, as previously explained, provided by the fluid within the work chamber, and accordingly the declutching action is necessarily obtained by an emptying of the work chamber. It will be understood that as an overload condition occurs on the output shaft the emptying of the work chamber should be effected rather rapidly in order to prevent breakage or wear of parts in the power system. Also, the fluid declutching action should preferably be

2

automatic and without necessity for actuation by human intervention or human control.

It is an object of the present invention to provide a fluid drive with a declutching mechanism having the above-mentioned desirable automatic characteristics.

A further object of the invention is to provide a fluid drive with a torque limiting or declutching mechanism which is of relatively simple construction and which, without extensive redesign, can be built to come into play at any desired percentage of slip between the impeller and runner.

It is a further object of the invention to provide a fluid drive with a declutching mechanism, the design of which is such as to permit it to empty the work chamber quickly or more slowly, the exact rate of emptying being varied by means of an easily effected structural alteration of the mechanism.

A further object of the invention is to provide a declutching mechanism which can be operatively utilized with a variable speed fluid drive, and which during normal operation of the fluid drive is ineffective to have any disadvantageous action on the fluid drive performance.

A general object of the invention is to provide a fluid drive with a declutching device having low manufacturing and maintenance costs.

Other objects of this invention will appear in the following description and appended claims, reference being had to the accompanying drawings forming a part of this specification wherein like reference characters designate corresponding parts in the several views.

In the drawings:

FIGURE 1 is a view taken through a fluid coupling equipped with one embodiment of the invention, with the coupling shown in operative position in a fluid circulating system;

FIG. 2 is a sectional view taken substantially on line 2—2 in FIG. 1.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring to FIG. 1 of the drawings, there is disclosed a fluid drive including a bottom or base wall 10 having an upstanding casing structure 12 secured thereto. The casing structure comprises a top wall 14, a pair of side walls 16, and a pair of end walls or bells 18 and 20. The end bells are removably but fixedly carried on vertical wall structures 22 and 24, the arrangement being such as to permit the end bells to be removed for inspection, replacement and repair of the fluid coupling components disposed within the casing structure.

End bell 18 mounts the bearing assembly 26 for the input shaft 28. End bell 20 mounts the bearing assemblies 30 and 31 for the output shaft 32. Bell 20 comprises two component parts numbered in the drawings as 21 and 23. Component 21 mounts anti-friction bearing assembly 30 for shaft 32, and component 23 mounts sleeve bearing 31 for shaft 32. It will be understood that the bearing-end bell relationships can be varied, and that the showings in the drawings are merely illustrative. The illustrated input shaft 28 is flanged as at 34 to form a mount for the impeller casing 36 and impeller 38. As shown in FIG. 1 the impeller casing extends beyond the impeller and is of a two-section construction. Section 42 of the casing extends inwardly as at 44, and a partition 48 is suitably carried on the casing so as to cooperate therewith in defining a scoop chamber 46. A series of

openings 50 are provided at the periphery of the partition to permit fluid to flow into the scoop chamber from the work chamber.

The work chamber is defined by the aforementioned impeller 38 and the runner 52, each of the impeller and runner having a series of radial vanes as at 54 and 56, said vanes being radially arranged as in the conventional practice.

In the illustrated embodiment the work chamber defined by the impeller and runner is supplied with working fluid from a fluid line 58, said line being connected to the work chamber via an annular chamber 60, a passageway 62 within the input shaft 28, and a passageway 64 located within the impeller. It will be understood that during rotation of the input shaft the fluid which is introduced into the space between impeller vanes 54 is given a vortical or whirling motion as indicated generally by the arrows 66.

The fluid is thrown centrifugally outwardly and travels between the impeller and runner vanes so as to transmit power from the impeller to the runner. Fluid occupies the annular space 68 and circulates through the openings 50 into the scoop chamber 46. The level of fluid within the scoop chamber is determinative of the amount of fluid within the work chamber, and as previously explained, the amount of fluid in the work chamber determines the extent of slip which exists between the impeller and runner.

To control and vary the quantity of fluid within the work chamber and scoop chamber there is provided a fluid-withdrawing means, shown in the illustrative embodiment as a scoop tube 70, said tube being of hollow construction and having a lip area 72 which dips into the rotating ring of fluid within the scoop chamber so as to cause the rapidly moving fluid to travel upwardly in the scoop tube as indicated by arrow 74. The scoop tube is carried on a shaft 76 which is bearinged in a fixed bushing or sleeve bearing 78 located on component 23 of end bell 20. The scoop tube per se is extended from a hub 80 which is provided with a passage 82 for directing the scoop tube fluid into the sump designated generally by the numeral 86. The exact construction and mounting of the scoop tube may be varied insofar as the present invention is concerned.

The entire system is installed with a sufficient amount of fluid to provide a sump liquid level 87 sufficient to form a source of fluid for the fluid pump 88. The pump may be of various different constructions, as for example a vane type construction, and may be powered in various different ways. One convenient method of powering the pump consists of employing a chain 90 trained around a sprocket 92 on input shaft 28 and a sprocket 94 on the pump shaft 96. The pump may be supplied with liquid through a port adjacent its lower end, and the liquid output may be directed through a conduit 98 into the conventional cooler 100. The cooled fluid may be then directed into the aforementioned line 58 and thence back to the impeller via the aforementioned passageways 62 and 64. A suitable diverter valve 59 may be provided for directing a portion of the cooler liquid into a line 61 bypassing the fluid drive.

The speed of the above-mentioned fluid drive is, as previously mentioned, controlled by the position of the scoop tube 70, and as will be noted from FIG. 1 the scoop tube position is controlled by the rotational position of its mounting shaft 76. This shaft carries a gear 77, the teeth of which mesh with the teeth of a toothed operator rack 102 carried on a slideable shaft 103. It will be understood that the rack-shaft means extends through and within the end bell 20 so as to be moved by an external control structure. This control structure may merely consist of a manually operable handle or actuator, or it may be operated automatically in response to variation in a particular control condition such as temperature change or fluid pressure development. The present invention is not concerned with the type of control structure employed, and hence details thereof are not illustrated.

It will be understood that while the drawings show the fluid-withdrawing device as consisting of a rotary scoop tube 70, yet other types of fluid-withdrawing constructions such as rectilinearly movable scoop tubes can be employed. Irrespective of the type of fluid-withdrawing means which is employed, it will be seen that during operation of the fluid drive the torque transmission from the impeller to the runner is determined by the amount of fluid in the scope chamber. With any substantial quantity of fluid in the work chamber, acceleration of the input shaft applies an added load on the output shaft. However, with the construction of the present invention special provision is made for avoiding any undesired load onto the output shaft during this acceleration period. In this connection it will be noted that the runner is provided with a series of protruding wall portions 104 arranged around its periphery. These wall portions are bored out to form the short circumferentially extending passageway sections 106. Longer radial passage sections 108 extend from sections 106, and short axial passage sections 110 extend from the radial sections. The three connected sections 106, 108 and 110 constitute a passageway herein designated by numeral 105.

In operation of the fluid drive, during periods of input shaft acceleration the impeller is rotating faster than the runner and the fluid which is discharged into the annular space 68 is constantly overtaking the passage sections 106. The velocity head of the fluid in space 68 is at this time sufficient to force the fluid to flow into the passage sections 106 and thence be directed axially as at 110 out of the fluid coupling. The passageway fluid may be discharged into the sump, either directly through the casting eye 111 or by first discharging into the scoop chamber. The nature of the discharge from passage sections 110 depends on such factors as the magnitude of the velocity head, the magnitude of the centrifugal head, and the size of the pasageway. In the illustrated embodiment each of the passage sections 110 is formed by an annular insert nozzle element 113, and it will be understood that all or some of the pasageways 105 may be effectively varied in size by suitable nozzle element construction procedures. By this arrangement fluid couplings having different operating characteristics can be obtained at very low added cost.

In use of the illustrated drive, during the acceleration period the amount of fluid within the work chamber will be somewhat less than the level which would ordinarily be dictated by the scoop tube 70 (due to the action of the passageway 105). There will therefore be a substantial declutching of the runner such as to provide a torque limiting action sufficient to safeguard the output shaft and provide a soft satisfactory acceleration action.

It will be understood that as the fluid drive comes up to speed the runner speed will approach the impeller speed and the fluid within the space 68 will not have sufficient velocity head to overtake the passages 105. The passages will thereby not interfere with the normal operation of the fluid drive under usual operational conditions.

As previously explained, in the presence of certain overload conditions on the output shaft it is desirable to declutch the runner from the impeller in order to prevent parts damage. With the illustrated device, in the event of an overload condition on the output shaft 32 the runner will necessarily reduce its speed, and the fluid within the space 68 will thereby be permitted to overtake the passageways 105 and flow inwardly therein so as to be discharged from the working circuit. The subtraction of the fluid from the work chamber through the passageways 105 serves to partially or wholly declutch the runner from the impeller and thereby prevents the overload condition on shaft 32 from having any adverse effect on the component mechanisms.

The time period necessary for effecting this declutching action is determined by the size and length of the pas-

sageways in relation to the other mechanisms of the fluid drive, and it will be understood that in general the speed of declutching may be increased by increasing the size of the passageways and decreasing their length. The size of the passageways may be increased by increasing the total number of passageways and/or increasing the cross-sectional area of each passageway. In the illustrated construction the cross sectional area of each passageway may be readily controlled by utilizing appropriate size inserts 113.

By choosing a suitable length for the passage sections 108 the declutching action can be set to come into play at any desired percentage of slip. This, if the passage sections 108 extend only a short distance inwardly from the outer periphery of the runner the velocity head of the fluid will be sufficient on a relatively small differential speed between impeller and runner to exhaust fluid from the work chamber in a manner to declutch the runner from the impeller. Under these conditions the declutching action will take place at a relatively small slip between the impeller and runner. By making the passage sections 108 extend further toward the axis of the fluid drive the fluid at 68 must acquire a relatively large velocity head before it can sufficiently overtake the passageways 105 so as to be exhausted from the work circuit. Therefore, under these design conditions the declutching action will take place at a relatively high percent of slip between the impeller and runner.

If desired certain ones of passage sections 108 may extend further radially inward than others, as for example as shown in FIG. 2 wherein four of the eight passage sections terminate inwardly of the other four. This passage arrangement is of advantage in that it permits a gradual, smooth declutching action, i.e. at a relatively small speed differential the shorter ones of passage sections 108 become operative and at a larger speed differential the longer ones of passage sections 108 become operative.

The drawings show the exhaust passageways 105 directly in the body of the runner. However, it will be appreciated that these passages could be formed by other means. For example, these passageways could if desired be constructed as separate tubes fastened onto the back of the runner. With such a construction the outer surfaces of the tubes could be made to have the desirable function of acting as fluid-engageable driving vanes for the runner.

Various other changes could be made without departing from the spirit of the invention as defined in the appended claims.

I claim:

1. In a fluid coupling, a housing defining a liquid reservoir, a toroidal work chamber within said housing comprising opposed axially aligned and spaced rotatable impeller and runner shells, mounted respectively on input and output shafts, means for continuously supplying liquid to said work chamber from said reservoir, a casing connected to said impeller shell and enclosing said runner shell in spaced relation to form one wall of a rotatable scoop chamber, a radial partition wall carried by said casing between said one wall and said runner to form the other wall of the scoop chamber and separate said work chamber from said scoop chamber, said casing and partition walls being spaced radially from said output shaft to form coaxial eyes opening from said work chamber into said housing and thus to said reservoir, said scoop chamber being coaxial to said work chamber and in free liquid communication therewith whereby the level of liquid in said scoop chamber determines the amount of liquid in said work chamber and the slip in said coupling, a scoop tube supported for radial adjustment in said scoop chamber and discharging to said reservoir for 75

controlling the amount of liquid in said scoop chamber and thus in said work chamber, means for adjusting said scoop tube,

scoop passage means extending radially inwardly through said runner from an inlet mouth in said work chamber at the periphery of said runner to an exhaust opening in the runner hub adjacent said output shaft,

and said exhaust opening extending axially to discharge the liquid through said eyes and into said housing during predetermined slip when said impeller appreciably overruns said runner.

2. In a fluid coupling including

a housing defining a liquid reservoir, a toroidal work chamber within said housing comprising opposed axially aligned and spaced rotatable impeller and runner shells, means for continuously supplying liquid to said work chamber from said reservoir,

a casing connected to said impeller shell and enclosing said runner shell in spaced relation to form one wall of a rotatable scoop chamber,

a partition wall carried by said casing between said one wall and said runner to form the other wall of said scoop chamber,

said casing and partition walls having eyes coaxial to said work chamber and opening from said work chamber into said housing,

said scoop chamber being coaxial to said work chamber and in free liquid communication with said work chamber whereby the level of liquid in said scoop chamber determines the amount of liquid in said work chamber and the slip in said coupling,

a scoop tube supported for radial adjustment in said scoop chamber and discharging to said reservoir for controlling the amount of liquid in said scoop chamber and thus in said work chamber,

and means for adjusting said scoop tube, the improvement of overload scoop passage means extending through said runner from an inlet mouth in said work chamber at the periphery of said runner to an exhaust opening in alignment with said eyes of said casing and partition walls,

and said exhaust opening being oriented to discharge through said eyes and into said housing during predetermined slip when said impeller overruns said runner.

3. In a fluid coupling including

a toroidal work chamber comprised of opposed impeller and runner shells,

means for continuously supplying working liquid to said work chamber,

a casing connected to said impeller shell and enclosing said runner shell in spaced relation to form a rotatable scoop chamber,

said scoop chamber having an eye coaxial to said work chamber,

said scoop chamber being coaxial to said work chamber and in free liquid communication with said work chamber whereby the level of liquid in said scoop chamber determines the amount of liquid in said work chamber and the slip in said coupling,

a scoop tube adjustable in said scoop chamber and discharging to said supply means for controlling the amount of liquid in said scoop chamber and thus in said work chamber,

and means for adjusting said scoop tube, the improvement of a passage extending through said runner from an inlet mouth at the periphery of said runner to an exhaust opening positioned radially inwardly of said inlet mouth,

and said exhaust opening being oriented to discharge through said eye during predetermined slip conditions when said coupling appreciably overruns said runner,

- and means for conducting said discharged fluid to said supply means.
4. In a fluid coupling including a toroidal work chamber comprising opposed impeller and runner shells, means for continuously supplying working liquid to said work chamber, casing means connected to said impeller shell to form a rotatable scoop chamber coaxial to said work chamber and in free liquid communication therewith whereby the level of liquid in said scoop chamber determines the amount of liquid in said work chamber and the slip in said coupling, said scoop chamber having an axial opening, a scoop tube adjustable in said scoop chamber and discharging to said supply means for controlling the amount of liquid in said scoop chamber and thus said work chamber, and means for adjusting said scoop tube, the improvement of scoop passage means extending through the back of said runner from an inlet mouth in said work chamber at the peripheral level of said runner to an exhaust opening centrally of said runner, and said exhaust opening being oriented to discharge through said axial opening of said scoop chamber during predetermined slip conditions when said impeller overruns said runner.
5. In a fluid coupling, a housing defining a liquid reservoir, a toroidal work chamber in said housing comprising opposed axially aligned and spaced rotatable impeller and runner shells, means for supplying liquid to said work chamber from said reservoir, a casing connected to said impeller shell and enclosing said runner shell in spaced relation to form one wall of a rotatable scoop chamber, a partition wall carried by said casing between said one wall and said runner to form the other wall of the scoop chamber, said partition wall having an eye coaxial to said work chamber and opening from said work chamber into said scoop chamber, said scoop chamber being coaxial to said work chamber and in free liquid communication with said work chamber whereby the level of liquid in said scoop chamber determines the amount of liquid in said work chamber and the slip in said coupling, a scoop tube adjustable in said scoop chamber and discharging to said reservoir to control the amount of liquid in said scoop chamber and thus in said work chamber, means for adjusting said scoop tube, a declutch passage extending from an inlet mouth positioned at the peripheral level of said runner to an exhaust opening positioned radially inwardly of said inlet mouth, and said exhaust opening being oriented to discharge through said eye during predetermined slip conditions of said impeller overrunning said runner.
6. In a fluid coupling, a toroidal work chamber defined by opposed impeller and runner shells, means for continuously supplying liquid to said work chamber, casing means connected to said impeller shell and enclosing said runner shell in spaced relation to form a rotatable chamber to hold a rotatable ring of liquid, said rotatable chamber being coaxial to said work chamber and in free liquid communication therewith whereby the level of liquid in said rotatable chamber determines the amount of liquid in said work chamber and the slip in said coupling,

5 10 15 20 25 30 35 40 45 50 55 60 65

- adjustable regulating means for regulating the quantity of liquid in said rotatable ring and thereby the amount of liquid in said work chamber, declutch passage means extending from an inlet mouth at the peripheral level of said runner to an exhaust opening positioned between said coupling axis and said inlet mouth, and said exhaust opening being oriented to discharge liquid out of said work chamber and back to said supply means.
7. In a fluid coupling, a toroidal work chamber defined by opposed impeller and runner shells, means for continuously supplying working liquid to said work chamber, casing means connected to said impeller shell and enclosing said runner shell in spaced relation to form an annular rotatable chamber to hold a rotating ring of liquid, said rotatable chamber being coaxial to said work chamber and in free liquid communication therewith whereby the level of liquid in said rotatable chamber determines the amount of liquid in said work chamber and the slip in the coupling, adjustable regulating means for regulating the quantity of liquid in said rotatable ring and thereby the amount of liquid in said work chamber, a plurality of declutch passages, each having an inlet mouth at about the outer peripheral level of said impeller and runner shells in said work chamber and extending to an exhaust opening between said coupling axis and said inlet mouth, at least some of said exhaust openings being positioned nearer the axis of said coupling than others, said exhaust openings being oriented to discharge liquid out of said work chamber and back to said supply means, and means for recycling liquid discharged from said exhaust openings back to said work chamber.
8. In a fluid coupling, a toroidal work chamber defined by opposed impeller and runner shells, means for supplying working liquid to said work chamber, a casing means connected to said impeller shell to form a rotatable chamber to hold a rotatable ring of liquid, said rotatable chamber being coaxial to said work chamber and in free liquid communication therewith whereby the level of liquid in said rotatable chamber determines the amount of liquid in said work chamber and the slip in the coupling, adjustable regulating means for regulating the quantity of liquid in said rotatable ring and thereby the amount of liquid in said work chamber, declutch passage means extending from an inlet mouth at about the outer peripheral level of said runner to an exhaust opening positioned between said coupling axis and said inlet mouth, said exhaust opening being oriented to discharge liquid out of said work chamber and back to said supply means, and means for recycling liquid exhausted from said discharge opening back to said work chamber.
